UNITED STATES PATENT OFFICE.

FRANÇOIS BAVEREY, OF LYON, FRANCE, ASSIGNOR TO SOCIETE DU CARBURATEUR ZENITH, OF LYON, FRANCE, A CORPORATION OF FRANCE.

CARBURETER FOR EXPLOSIVE-MOTORS.

1,265,588.

Specification of Letters Patent. Patented May 7, 1918.

Original application filed February 7, 1914, Serial No. 817,277. Divided and this application filed March 29, 1917. Serial No. 158,234.

To all whom it may concern:

Be it known that I, FRANÇOIS BAVEREY, a citizen of the French Republic, residing at Lyon, in France, have invented certain new and useful Improvements in Carbureters for Explosive-Motors, of which the following is a specification, reference being had to the accompanying drawings, forming part of this specification, in which:

10 Figure 1 illustrates the construction of one form of apparatus diagrammatically.

Fig. 2 is a plan view partially in section showing one form of construction of an apparatus built in accordance with my invention.

15 Fig. 3 is a detail perspective view of the air tube inlet or casing.

Fig. 4 is a perspective view of the valve which is rotatably mounted in the casing shown in Fig. 3.

20 Figs. 5, 6, 7, 8 and 9 are sectional views, respectively, on the lines B—B, C—C, D—D, E—E, and F—F of Fig. 2, showing portions thereof.

25 This invention relates to improvements in carbureters for explosive engines, and is a division of my copending application Serial No. 817,277, filed February 7, 1914.

One of the objects of my invention is to 30 provide means for simultaneously varying the air supply and the supply of fuel passing to the engine.

I accomplish this by supplying an emulsion rich in fuel to the air intake passage through a plurality of nozzles, and so arrange said nozzles with respect to the air intake passage that the air supply and fuel supply passing to the engine are simultaneously regulated, so as to insure a good mixture for all positions of the throttle valve and all speeds of the engine.

The precise nature of my invention will be best understood by reference to the accompanying drawings, it being premised, 45 however, that various changes may be made in the details of construction and general arrangement of the parts, without departing from the spirit and scope of my invention as defined in the appended claims.

50 Referring to the diagram shown in Fig. 1, the reference character 2 designates a casing having a passage 3 therethrough which is of

rectangular form, and which passage is arranged to communicate with the intake to the engine. Slidably mounted within this 55 passage 3 is a throttle valve 4, and extending into the passage from the intake side thereof are three nozzles 5, 6 and 7, which are arranged to deliver an emulsion of fuel and air to the air intake channel. The ends of these 60 nozzles are rectangular in cross section, and the three nozzles extend entirely across the width of the passage 3, so that when the throttle valve is moved to its full open position the mouths of the ends of the nozzles 65 5, 6 and 7 will be entirely uncovered. These nozzles are arranged in such a manner that the size of the openings uncovered and covered by the throttle valve will vary in proportion to the size of the air intake under 70 the control of the throttle valve, and as the nozzles are placed side by side, the nozzle 5 will be fully uncovered before the throttle valve starts to uncover the nozzle 6, the arrangement being such that the various nozzles 75 will be opened successively.

In Figs. 2 to 8 I have shown another form of device in which I have used the same reference characters for the same parts. In this construction the casing 2 is 80 provided with a cylindrical chamber 8 for the reception of a rotary throttle valve 4, which is provided with a through passage 9 which connects the intake and outlet ends of the passage 3 through the casing and 85 forms a continuation thereof when the valve is in its full open position, as shown in Fig. 2. Connected to one side of this casing 2 is a cap 10, which forms one side of the valve casing, and supported from this cap 10 is a constant level reservoir 13. Formed within the casing 2 at one side thereof are a plurality of V-shaped recesses 14, 15 and 16 which are arranged to communicate with the chamber 8. Formed with in the cap 10 are emulsion passages 17, 18 and 19, which communicate at one end with the recesses 14, 15 and 16, respectively, and are arranged to feed emulsion to the air passage when they are uncovered by the 95 valve 4 as hereinafter described. Formed integrally with the cap 10 and the constant level reservoir is a shell 20 having a chamber 21 formed in the lower end thereof, 100

which is in communication with the constant level chamber by means of a channel 22, so that fuel is constantly fed to said chamber. Formed within this shell 20 is an atmospheric well 23 which receives fuel from the chamber 21 through a calibrated opening 24, and 25 is a screw cap for the atmospheric well having screens 26 through which the air can pass to the well. The emulsion passage 19 communicates with the atmospheric well and is provided with a Venturi tube 27, and 28 is a suction controlled feed jet communicating with the passage 19 and which receives fuel through the calibrated opening 29 which communicates with the chamber 21. 30 is a compensating jet communicating with the passage 19 and the well 23. The passage 18 is also provided with a Venturi tube 31 which communicates with the atmospheric well 23, and 32 is a suction controlled feed jet communicating with the passage 18 and which receives fuel from the chamber 21 through a calibrated opening 33. 34 is a compensating jet communicating with the passage 18 and the well 23 slightly above the lower end of the compensating jet 30 for the passage 19, the jets 30 and 34 are supplied with a measured quantity of gasoline passing through the calibrated opening 24. When the throttle is shifted so as to uncover emulsion passage 18 and to retain emulsion passage 19 covered, the amount of gasoline fed to passage 34 is regulated by the calibrated orifice 24 and the height at which passage 34 opens into well 33 as this determines the effective head causing the flow through the orifice 24. When passage 19 is uncovered by the throttle the flow through passage 34 ceases and the compensating gasoline is added entirely through passage 30, the amount being constant per unit of time, and being determined by the calibrated orifice 24 and by the height at which passage 30 opens into the well 23. As the passage 34 opens above passage 30, it follows that the compensating gasoline furnished to the emulsion passage 18 is smaller in amount per unit of time than the compensating gasoline supplied to emulsion passage 19. The passage 17 is in direct communication with the constant level reservoir 18 through the calibrated opening 35, and 36 is an air inlet opening for the passage 17, the size of which may be adjusted by means of the screw 37.

It will readily be understood by those familiar with the art that the same results for feeding the compensating gasoline may be obtained if emulsion passages 18 and 19 had independent supplies of compensating gasoline, and which might be arranged in other ways than the specific illustration in the drawings.

The operation of this device will readily be understood from the description of the

diagram shown in Fig. 1, but in this case the valve is rotated so as to gradually cut off the air supply, and at the same time cut off communication between the passage 9 in the valve 4 and the recesses 14, 15 and 16. 70 As shown in Fig. 2 the valve is in its full open position, so that a full supply of fuel and air is fed to the engine, but when the valve is shifted a predetermined distance the feed from passage 19 through the recess 16 75 will be cut off, and when moved still farther the feed from passage 18 through the recess 15 will be cut off.

The advantages of my invention result from the provision of a plurality of jets for 80 feeding emulsion to an air intake, together with valve means for proportionately varying the size of the emulsion openings and the size of the air intake, and successively covering and uncovering the emulsion 85 openings.

I claim:

1. In a carbureter, the combination of an intake arranged to supply a fuel mixture to the engine, an air passage leading to the intake, a plurality of jets each having a passage leading therefrom to the intake, said passage being small relative to the air passage, means for admitting air to said passages to form an emulsion, and a throttle 90 arranged to simultaneously vary the size of the air intake and the area of the emulsion passages, substantially as described.

2. In a carbureter, the combination of an air intake arranged to supply a fuel mixture to the engine, a plurality of jets each having a passage leading therefrom into the air intake, means for admitting air to said passages to form an emulsion, and a throttle 100 arranged to simultaneously vary the size of the air intake and to successively open or close the emulsion passages, substantially as described.

3. In a carbureter having a constant level chamber and a well communicating with the atmosphere, the combination of an air intake arranged to supply a fuel mixture to the engine, a plurality of jets each having a passage leading therefrom into the air intake, means for admitting air to said passages to 110 form an emulsion, some of said jets opening below the level of the liquid in the constant level reservoir into the well, and a throttle arranged to simultaneously vary the area of the air intake and the area of the emulsion 120 passages, substantially as described.

4. In a carbureter, an air conduit, a plurality of fuel conduits discharging thereto, some of said fuel conduits being provided with two sources of fuel supply, one 125 providing a supply variable per unit of time, and one constant per unit of time, and a throttle arranged to simultaneously vary the area of the air conduit and the area of the fuel conduits, substantially as described. 130

5. In a carbureter, an air conduit, a plurality of fuel conduits subject to the influence of air passing through the air conduit, means for admitting air to said conduits to form an emulsion, all of said conduits having a suction controlled fuel feed, some of said fuel conduits having another fuel feed giving a fuel supply increasing at a less rate than the air supply, and a throttle arranged to simultaneously vary the area of the air conduit and the area of the openings from the fuel conduits thereto, substantially as described.
6. A carbureter having an air intake, a plurality of passages leading thereto, said passages being small relative to the air intake, means for feeding air and fuel to each of said passages, a throttle valve in said air intake arranged to vary the size of the opening therethrough, said throttle valve also being arranged to successively open and close the emulsion passages successively leading to the air intake, substantially as described.
7. A carbureter comprising a casing having a through opening, one end of said opening being arranged to communicate with the intake of an engine while the other end thereof is open to the atmosphere, a rotary valve in said casing having an opening therethrough arranged to register with the opening through the casing, a plurality of emulsion passages communicating with the opening through the valve when the valve is in its full open position, a jet communicating with each passage, means for feeding fuel to each of said jets, and means for feeding air to each of said passages, said valve being arranged to successively close all the emulsion passages and to simultaneously re-
- duce the size of the through opening, substantially as described.
8. A carbureter having an intake arranged to supply a fuel mixture to the engine, an air passage leading thereto, a well open at one end to the atmosphere, means for feeding fuel to the well, a plurality of emulsion passages communicating with the intake, means for admitting air to each passage, a plurality of sunken jets communicating with the well and each emulsion passage, and a valve arranged to simultaneously vary the size of the intake and the area of the emulsion passages, substantially as described. 55
9. A carbureter having a casing with an opening therethrough, one end of said opening communicating with the intake of the engine, the other end thereof being open to the atmosphere, a valve opening through said casing having an opening therethrough arranged to register with the opening through the casing, a plurality of emulsion passages in the valve casing communicating with the valve opening adjacent to the opening for the air, the opening through said valve being arranged to communicate with the emulsion passages when the valve is in its open position, the valve being arranged to successively close the emulsion 70 passages and simultaneously reduce the size of the passage through the casing, substantially as described. 65

In testimony whereof, I have hereunto set my hand.

FRANÇOIS BAVEREY.
